TELEPHONE SYSTEM

Merton R. Miller, Evanston, Ill., assignor, by
mesne assignments, to Associated Electric Laboratories, Inc., Chicago, Ill., a corporation of
Delaware

Application July 15, 1935, Serial No. 31,398

11 Claims. (Cl. 179—1.5)

The present invention relates in general to telephone systems and more in particular to secret telephone systems, in which intelligible conversation cannot be picked up by listening in at intermediate points, and the object is to provide an efficient and desirable system of this character.

A special feature is the arrangement of a system of this character in which the secrecy securing equipment is located at the subscriber's premises, thereby eliminating the possibility of surreptitious listening by employees at a public telephone exchange through which connections are set up.

15 The invention will be described hereinafter with reference to the accompanying drawing, which shows diagrammatically the apparatus and circuits involved.

The invention is applicable to numerous situations, but for convenience it will be assumed to be in use for providing secret communication between two offices of some organization having confidential business that has to be discussed by telephone. These offices may be in the same or 20 in different cities. Each office may be equipped with a private branch exchange telephone system, or P. B. X., having local telephones and trunk lines to the nearest exchange of the public telephone system.

25 Referring now to the drawing, the equipment there shown is located at the P. B. X. switchboard at one of the offices of the organization. There is a duplicate equipment at the P. B. X. switchboard in the other office.

30 The four jacks J¹ to J⁴, inclusive, are outgoing trunk jacks at the P. B. X. switchboard and give access to four outgoing trunks extending to the nearest public exchange. There may be more than the four trunk lines shown. The four plugs 35 P¹ to P⁴, inclusive, are associated with the secret service equipment and are used to connect such equipment up to four of the regular outgoing trunk lines such as those terminating in jacks J¹ to J⁴. Jacks J⁵ to J⁸, inclusive, are jacks of the 40 secret system and give access to four secret channels for conversation. These latter jacks appear on the P. B. X. switchboard as special jacks, and the same is true of the plugs P¹ to P⁴.

45 The P. B. X. operator is also provided with four sets of coding keys A, B, C, and D, and with a distributor DR. The keys should be mounted in conveniently accessible manner. The distributor and driving means may be located in rear of the face panel of the switchboard if room is available; otherwise it may be mounted in a small cabinet

set on top of the switchboard or on a table alongside of it. If a separate cabinet is used for the distributor the key sets A to D may be included in it also.

5 The distributor DR comprises a face plate 5 having conducting rings and segments as shown and is rotatably mounted on a hub 8. Connections to the rings and segments of the distributor are made by means of flexible leads which permit rotation of the face plate 5 through about 360°. 10 The face plate 5 has a toothed rim cooperating with a worm 6 which is turned by a hand wheel or dial 7. The dial 7 is accessible to the operator. The brushes of the distributor are attached to an arm 10, mounted on a shaft 9. The shaft 9 is 15 rotated at a speed of about two to four times a second by a motor 12 through a reduction gear box 11. The motor 12 is a constant speed motor, preferably a synchronous motor.

20 The reference character S indicates a switch for connecting up a source of current to operate the distributor motor. Current for operating the tone buzzer 13 is also supplied through the switch S.

25 Proceeding now with the explanation of the operation of the system, the equipment may be connected up at both ends simultaneously by the P. B. X. operators according to pre-arrangement, or either operator may initiate the connection. Assuming the operator having the equipment shown in the drawing desires to set up the secret system, she will first actuate the No. 2 key in each of her key sets A to D, inclusive, and will then throw the switch S to start the distributor motor 12. The operator then plugs into 30 the first secret jack J⁵ with one of her regular cord circuits and inserts the first plug P¹ into an idle outgoing trunk jack such as J¹. If common battery signalling is used on the trunk lines the act of plugging into the outgoing trunk, 35 which puts a bridge across the trunk conductors, will signal the operator at the public exchange; otherwise the P. B. X. operator will ring on the trunk line in the usual manner, the repeating coils of the secret equipment being adapted to 40 pass ringing current as well as voice currents.

45 Upon obtaining a response from the operator at the public exchange, the P. B. X. operator will order up a connection in the usual manner to the distant office of the firm, where the call will come in on a trunk jack similar to jacks J¹—J⁴. The signalling and supervisory equipment is not shown, but may be of the usual character. The distant P. B. X. operator answers the call with 50 one of her regular cord circuits and upon learn- 55

ing that the other P. B. X. operator is calling and wants to set up the secret system she operates the No. 2 keys in her key sets A to D, inclusive, and throws her switch S, the same as was done at the originating P. B. X. The distant P. B. X. operator then transfers her cord circuit to the first jack such as J⁶ of her secret equipment and inserts the plug corresponding to plug P¹ in the trunk line over which the call was received. The two operators may then converse to check the continuity of the talking circuit through the secret equipment at both ends. These circuits will be more fully explained later, but it may be stated that with the same keys operated in all key sets only a straight non-secret conversation over the single channel so far set up is involved.

The originating P. B. X. operator will now proceed to set up three more calls to the distant P. B. X. in the same manner, using successively the jacks J⁶, J⁷, and J⁸, which are connected up to outgoing trunk lines by inserting plugs P² to P⁴ into outgoing trunk jacks such as J² to J⁴. As the calls are received at the distant P. B. X. the operator answers by inserting plugs which correspond to plugs P² to P⁴ in the trunk jacks over which the calls are received, care being taken that corresponding plugs such as P² at the two P. B. X. switchboards are used for the same connection. When the four connections are finally established there will be four separate telephone channels interconnecting the two P. B. X. switchboards.

The two P. B. X. operators will next set their key sets according to some prearranged code number. Assuming that the number is 2431, the operator at the originating P. B. X. will operate the No. 2 key in key set A, or rather will leave this key in operated position, and will operate the No. 4 key in key set B, the No. 3 key in key set C, and the No. 1 key in key set D. The operator at the distant exchange will do likewise.

One of the secret channels may be used as an order wire, although a regular connection could be put through and used for that purpose as soon as the system is properly synchronized. It will be assumed, therefore, that the originating operator leaves up her cord circuit in jack J⁸ and stays on the line with her headset. At the distant P. B. X. the operator will plug into the corresponding jack and will then proceed to synchronize her distributor with the distributor at the originating P. B. X. In order to accomplish this the operator will rotate the face plate of her distributor by means of her dial such as 7 until the channel becomes clear and she can converse with the originating operator. Either operator could, of course, perform this operation as both distributors are adjustable.

Assuming now that the originating operator has a call for a secret channel to the distant office of the firm, she will connect the calling party with a secret service jack such as J⁶ by means of one of her regular cord circuits, and will transmit the number of the channel used and also the name or number of the called party to the distant P. B. X. operator over the channel being used as the order wire. The distant operator will therefore connect up the called party to the channel terminating in her jack J⁶, and the calling and called parties can then converse as desired.

Other secret connections can also be set up over the remaining channels. Either operator may, of course, originate calls, transmitting the necessary

information over the order wire to the other operator.

The circuits through the secret equipment will now be explained more in detail in order that the manner in which secrecy is secured may be fully understood. Considering a connection set up by way of jack J⁵ at the originating P. B. X. and the corresponding jack at the distant P. B. X., it will be observed that with the connection established the talking circuit from the local party in the originating P. B. X. will be extended through springs of jack J⁵ to the repeating coil R⁵. With the distributor arm 10 in the position shown in the drawing the right-hand winding of repeating coil R⁵ is connected over conductor 20, key No. 3 of key set C, conductor 29^k, brush set 46, and conductor 25 to the left-hand winding of repeating coil R². The right-hand windings of repeating coils R⁵—R⁸ and the left hand windings of repeating coils R¹—R⁴ are connected to a common conductor 48, or to ground, and consequently the right-hand winding of repeating coil R⁵ will be connected in series with the left-hand winding of repeating coil R². Thus the talking circuit will extend from jack J⁵ by way of repeating coil R⁵, key set C, distributor DR in position shown, repeating coil R², plug P², and jack J² to the second inter-exchange telephone channel, which is now set up over jack J¹. At the distant P. B. X. this telephone channel continues by way of a plug similar to P², repeating coil corresponding to R², distributor such as DR (now running in synchronism with distributor DR), a key set such as C to a jack such as J⁵ terminating the other end of the secret channel in use.

As the distributor arm 10 moves around it shortly enters the quadrant associated with key set B, whereupon the right-hand winding of repeating coil R⁵ will be connected with the left-hand winding of repeating coil R³ over conductor 20, key No. 4 of key set B, conductor 34, brush set 45, and conductor 26. The talking circuit then extends from jack J⁵ by way of repeating coil R⁵, key set B, distributor DR, repeating coil R³, plug P³, and jack J³ to the third telephone channel set up to the distant P. B. X. At the distant P. B. X. the distributor arm has moved around to the B quadrant also and consequently the third channel is connected through to the jack corresponding to jack J⁵ terminating the secret channel, thus maintaining the talking circuit, although the third telephone channel has been substituted for the second.

When the distributor arm 10 passes into the quadrant associated with key set A, the right-hand winding of repeating coil R⁵ will be connected with the left-hand winding of repeating coil R¹ over conductor 20, key No. 2 in key set A, conductor 36, brush set 41, and conductor 24. The talking circuit now extends from jack J⁵ by way of repeating coils R⁵ and R¹, plug P¹, and jack J¹ to the first telephone channel, i. e., the first telephone channel is substituted for the third. The same substitution is made by the distributor at the distant P. B. X. and the talking circuit is maintained.

When the distributor arm 10 passes into the quadrant associated with key set D, the right-hand winding of repeating coil R⁵ will be connected with the left-hand winding of repeating coil R⁴ over conductor 20, key No. 1 of key set D, conductor 43, brush set 44, and conductor 27, whereupon the fourth telephone channel over jack J⁴ will be substituted for the first channel over Jack J¹. The same substitution is made by the distrib-

utor at the distant P. B. X. so it will be seen that the talking circuit has been maintained intact throughout one complete revolution of the distributors notwithstanding that it has included successively the second, third, first, and fourth telephone channels.

5 The distributors keep on rotating and the same cycle of substitutions as described above is repeated over and over again as long as the conversation keeps on. When the parties finish the P. B. X. operators are notified in the usual way by their local supervisory signals and will pull down the connection.

10 So far the explanation has dealt only with the secret channel terminating in jack J^5 , but it will be clear that the other three secret channels terminating in jacks J^6 — J^8 are each switched by the distributors from one telephone channel to another similar to what is done with the first secret channel. To avoid a tedious detailed explanation a table has been prepared showing all the connections between the secret jacks J^5 — J^8 and the outgoing trunk jacks J^1 — J^4 throughout a complete rotation of the distributor. In compiling this table it was assumed that plugs P^1 — P^4 are inserted in jacks J^1 — J^4 , respectively, and that the code number 2431 has been set up on the key sets A—D.

Quadrant C

30 Jack J^5 connected to jack J^2
Jack J^6 connected to jack J^1
Jack J^7 connected to jack J^4
Jack J^8 connected to jack J^3

Quadrant B

35 Jack J^5 connected to jack J^3
Jack J^6 connected to jack J^2
Jack J^7 connected to jack J^1
Jack J^8 connected to jack J^4

Quadrant A

40 Jack J^5 connected to jack J^1
Jack J^6 connected to jack J^4
Jack J^7 connected to jack J^3
Jack J^8 connected to jack J^2

Quadrant D

45 Jack J^5 connected to jack J^4
Jack J^6 connected to jack J^3
Jack J^7 connected to jack J^2
Jack J^8 connected to jack J^1

It will be clear now that in the operation of the system, each secret channel is switched rapidly 55 from one telephone channel to another in accordance with a code, so that only one fourth of any given conversation will appear on any one telephone channel. Thus anyone listening in on any telephone channel, as at the public exchange, 60 or by tapping a telephone line outside the premises of the P. B. X. subscriber, will be unable to hear anything intelligible, even with the equipment as thus far described. The listener would hear one fourth of each secret conversation going on, as each secret channel would use the tapped line for one fourth of the time, but the part of each conversation thus picked up would be chopped up into fragments interspersed between fragments of the other conversations. The speed of 65 the distributors is high enough so that no complete words appear with the result that the voice currents picked up make a hopeless jumble of sound.

70 However, with only one secret channel in use the conversation could be picked up by means of

a special circuit arrangement which would permit listening in on all four telephone channels simultaneously. In order to defeat the success of such a scheme each secret channel is normally connected at the springs of the associated jack 5 such as J^5 with a source of tone current. Thus the drawing shows the left-hand winding of repeating coil R^5 connected by way of normally closed contacts of jack J^5 and conductors 50 and 51 with the buzzer 13, which is in operation continuously while the switch S is closed. The other three secret channels are connected to the buzzer 13 in the same way. At the other P. B. X. there is a buzzer similar to 13, which is connected up 10 the same way. The distant buzzer 13 may be of 15 a different frequency than the buzzer 13, but both preferably generate complex tone currents which are within the voice frequency range.

Thus it will be seen that each secret channel 20 carries tone currents when not connected up for conversation, and that these tone currents are switched from one telephone channel to another 25 the same as voice currents, whereby any conversation over a secret channel is effectually mixed either with tones or other conversations, or both, so as to prevent interception by listening in on any number of the telephone channels.

The successful operation of the system, of course depends on maintaining the two distributors in fairly close synchronism. If the synchronous motors driving the distributors are supplied from the same inter-connected power system, there will be no trouble at all on this account, and the two distributors after once being adjusted will stay together for a long time. If the motors 30 are supplied from different power systems, as might be the case if the P. B. X. switchboards are located in cities far apart, more frequent 35 adjustments will be necessary. These adjustments are readily taken care of by the P. B. X. operators, especially if one secret channel is used for orderwire purposes. The operators stay on this channel all the time, except when answering other calls, and will at once detect any departure from 40 synchronism and correct it.

In order to prevent the interception of conversations by the use at some intermediate point of equipment such as is shown, which might readily be built by anyone knowing the principle employed, the P. B. X. operators are preferably 50 instructed to change the codes at frequent intervals. In order to avoid the necessity of transmitting code numbers by telephone, the operators may be each provided with a list of code numbers, 55 which are to be used successively. With this plan it is only necessary for one operator to tell the other operator to change codes, whereupon both operators will set up the next code to be used. The change is preferably effected when all secret 60 channels are idle, but if this is impossible it can be accomplished without interrupting any conversation by depressing keys in corresponding key sets simultaneously on signals transmitted by one of the operators.

As illustrated the equipment provides for four 65 digit codes which ordinarily will give an adequate degree of security. Greater complexity can be secured by providing five or six key sets instead of four, and by changing the distributor segments to correspond.

The use of one wire or grounded circuits through the secret equipment simplifies the keys and the distributor and since these circuits are entirely local and very short there will ordinarily be no trouble from noise or cross-talk. However, 75

if desired, additional springs may be added to the keys and additional segments to the distributor so as to carry through both sides of each secret channel and provide full metallic circuits throughout.

The invention having been described; that which is believed to be new and for which the protection of Letters Patent is desired will be pointed out in the appended claims.

10 What is claimed is:

1. In a secret communication system, two telephone stations, a plurality of telephone channels extending between said stations, automatic means at each station for connecting a telephone to said channels successively, and coding means at each station for predetermining the order in which said channels are used, each coding means comprising a plurality of selectively operable switching devices operable at will to change the order of use.

2. In a secret communication system, two telephone stations, a plurality of telephone channels extending between said stations, automatic means at each station for connecting a telephone to said channels successively, a source of tone current, and means for connecting said tone source to each channel at times when said telephones are not connected thereto.

3. In a secret communication system, a plurality of telephone channels, a transmitting circuit, means for breaking a conversation occurring on said circuit into sections, means for distributing said sections to said channels in predetermined order, and coding means comprising a set of keys for changing the order at will.

4. In a secret communication system, a plurality of secret channels, a plurality of telephone channels, means for switching each secret channel from one telephone channel to another periodically, whereby the speech currents on any telephone channel will be a mixture of speech currents from said secret channels, and means operable at will while said switching means is operating to cancel the effect thereof, whereby each secret channel can be maintained in connection with a particular telephone channel.

5. In a secret communication system, a plurality of secret channels, means for mixing speech currents from channels in use before transmitting such speech currents, and means for maintaining tone currents of audible frequency on channels not in use so that the full number of audible frequency currents will always be available for mixing purposes whether all channels are in use for conversation or not.

6. In a secret communication system, a transmitting circuit, a telephone channel, means for

breaking a conversation occurring on said circuit into sections and for transmitting non-contiguous sections over said channel, a source of tone current, and means for transmitting tone current over said channel in the intervals between the transmission of sections of conversation.

7. In a secret communication system, a telephone circuit, a plurality of other circuits, a rotary distributor for connecting said first circuit to said other circuits successively, said distributor comprising a plurality of angularly spaced sections, and coding means for predetermining the order in which said other circuits are connected to, said coding means comprising a plurality of groups of keys, one group for each of said sections.

8. In a secret communication system, two telephone circuits, a plurality of intermediate circuits, means including two distributors for utilizing said intermediate circuits successively to connect said telephone circuits, and means for independently adjusting one of said distributors to insure that said telephone circuits are connected simultaneously to each intermediate circuit.

9. In a secret communication system, a plurality of secret channels, a plurality of telephone channels, means including a distributor for connecting said secret channels, respectively, with said telephone channels, each secret channel being maintained in connection with a particular telephone channel, and means for altering the distributor connections at will to cause each secret channel to be switched periodically to a different telephone channel.

10. In a P. B. X. switchboard including answering jacks, outgoing trunk jacks and cords for connecting them, secret service arrangements comprising secret service jacks to which said answering jacks may be connected by said cords, secret service plugs adapted to cooperate with said trunk jacks, speaking connections between said secret service jacks and secret service plugs, and means including a distributor for continuously changing said connections so that each secret service Jack is repeatedly connected to said secret service plugs in succession one at a time.

11. A switchboard as set forth in claim 10, characterized by the provision of speaking connections each including a single wire passing through the distributor and a common ground return conductor, and repeating coils for converting such single wire grounded circuits to metallic circuits at each secret service jack and plug.

MERTON R. MILLER.
